US00D535723S

(12) **United States Design Patent** (10) **Patent No.:** **US D535,723 S**
Veltz (45) **Date of Patent:** **** Jan. 23, 2007**

(54) SPOUT	D325,772 S	4/1992 Carr
(75) Inventor: Jason D. Veltz , Laguna Hills, CA (US)	D325,773 S	4/1992 Paul
(73) Assignee: Newfrey LLC , Newark, DE (US)	D326,504 S	5/1992 Robbins
(**) Term: 14 Years	D327,531 S	6/1992 Ko
(21) Appl. No.: 29/244,049	D327,532 S	6/1992 Ko
(22) Filed: Dec. 2, 2005	D332,135 S	12/1992 Bonnell
(51) LOC (8) Cl. 23-01	D334,230 S	3/1993 Bonnell
(52) U.S. Cl. D23/238	D340,968 S	11/1993 McKeone et al.
(58) Field of Classification Search D23/238-257; 4/675-678; 137/801	D347,268 S	5/1994 Paul
See application file for complete search history.	D348,307 S	6/1994 Gottwald

Primary Examiner—Louis S. Zarfas*Assistant Examiner*—Gregory Andoll(74) *Attorney, Agent, or Firm*—Richard J. Veltman; John D. Del Ponti**(57) CLAIM**

The ornamental design for a spout, as shown and described.

DESCRIPTION

FIG. 1 is a perspective view of the new design for a spout; FIG. 2 is a front view of the new design for a spout; FIG. 3 is a back view of the new design for a spout; FIG. 4 is a top view of the new design for a spout; FIG. 5 is a bottom view of the new design for a spout; and, FIG. 6 is a right side view of the new design for a spout, the left side view being a mirror image.

The broken lines in the Figures are for illustrative purposes only and form no part of the claimed design.
